COIL WINDING AND SETTING MACHINE

William Kaupert, Jamaica, N. Y.

Application August 3, 1935, Serial No. 34,588

10 Claims. (Cl. 140—92.2)

This invention relates to improvements in coil winding machines and has particular reference to a method for forming or setting the wound coils to a desirable shape for use in connection with fields of electric motors or the like.

The principal object of this invention is to provide a collapsible form for winding one or more coils from a continuous strand of wire so as to eliminate the usual soldered connections between 10 coils in a group.

A further object is to provide a means for setting a coil or group of coils to a desirable shape as hereinafter described without removing them from the winding form.

Further objects and advantages of this invention will be apparent from the following description when read in connection with the accompanying drawings illustrating the preferred embodiment thereof in which:

Figure 1 is an isometric view of the complete coil winding device.

Figure 2 is a top plan view of the same.

Figure 3 is an end elevational view of Figure 2.

Figure 4 is a longitudinal sectional view taken substantially on line 4—4 of Figure 2.

Figure 5 is a side elevational view of Figure 2.

Figure 6 is a similar side elevational view of

Figure 2, with the winding combs in the setting position.

Figure 7 is a top elevational view of a group of coils as wound and set on this device similar to the set coil indicated in Figure 2.

Figure 8 is an end elevational view of Figure 7.

Figure 9 is an enlarged cross sectional view taken substantially on line 9—9 of Figure 4.

Figure 10 is an enlarged cross sectional view taken substantially on line 10—10 of Figure 2.

Figure 11 is a fragmentary isometric view of one of the parts.

Figure 12 is a top elevational view of a group of coils, wound on this device, before the setting operation.

Similar numerals refer to similar parts throughout the several views.

Referring to Figure 2, crosshead 10 is attached to a threaded chuck 11 by means of machine screws 12 which also support the side members 13 and 14 to crosshead 10. Spacing blocks 15 and 16 separate members 13 and 14 and are held

in place by bolts and nuts 17 and 18. Threaded operating shaft 19 is provided with right and left hand threads meeting at its center as more clearly illustrated in Figure 4. Operating shaft 19 is not threaded at its points of support in blocks 15 and 16 and the collar 20, an integral part of

operating shaft 19, maintains shaft 19 centered between the spacing blocks 15 and 16. Operating shaft 19 has an extended square shank 21 to receive operating handle 22 as shown in Figure 2. Operating shaft 19 is in threaded engagement with extended lugs of combs 23 and 24. Pins protruding from the sides of combs 23 and 24, in Figures 4 and 9, engage in grooves 25 and 26 of side members 13 and 14 which form a channel to guide the movement of the combs. 5

In Figures 2 and 3, side arms 27 engage in slots 28 of crosshead 10 and are secured therein by means of shoulders 29, washers 30, nuts 31 and the threaded extensions 32 of side arms 27. Guide 33, also illustrated in Figure 11, is an integral 15 part of shoulder 29 and engages in slot 28 to maintain a nonrotating relationship with crosshead 10. Side plates 34 in Figures 2, 5, 6 and 10 are attached to side arms 27 by means of rivets 35 forming a top and a bottom channel and are 20 provided with slots 36 and 37 to receive pins protruding from the sides of combs 38 and 39. End combs 40, in Figures 1 and 2, are mounted on legs 41 which pass through openings in side arms 27 and plates 34 and are set to the desired adjustment by means of pins inserted in spaced holes 43. 25

Equalizing bars 44 and 45 in Figures 2, 5 and 6 are inserted in corresponding slots of the upper and lower combs of this device. End plate 46 in 30 Figures 1 and 2, tends to support side arms 27 and operating shaft 19 in a relationship similar to that of crosshead 10. Slots 47, in end plate 46, permit adjustment of side arms 27. In Figures 2 and 5, coil 49 is indicated in the initial wound 35 position. Coil 50 in Figures 2 and 6, represents a coil in a set or formed position. A group of coils 49 in Figure 12 are indicated as wound from a continuous strand of wire. A group of coils 50 in Figure 7, are illustrated after they have been 40 set or formed to the indicated shape.

In operation, this coil winding device is attached to any rotating head, such as the headstock of a lathe or the like, by means of threaded chuck 11 in Figure 2. End combs 40 are then set and 45 locked in the initial winding position by means of pins 42 inserted in spaced holes 43 of legs 41 as indicated by the dotted lines. A coil 49, also shown by dotted lines, is then wound on this device through all the combs and in corresponding 50 slots in the conventional manner. The combs 38 and 39 are in the position indicated in Figure 5.

After the coil is wound, equalizing bar 44, preferably of a width equal to the space between the teeth of the winding combs, is inserted in a slot 55

of comb 23, engaging also in corresponding slots of combs 38. Similarly, equalizing bar 45 is inserted in a slot of comb 24 engaging also in corresponding slots of combs 39. Pins 42 are then 5 withdrawn from holes 43 and handle 22 is inserted on shank 21 and operated to rotate operating shaft 19 in a counter-clockwise direction. Combs 23 and 24 in Figure 4, are moved in opposite directions by means of the threaded engagement of operating shaft 19 with the extended lugs of combs 23 and 24. Grooves 25 and 26 engage the pins attached to sides of combs 23 and 24 to facilitate the movement of said combs in the channel-like structure formed by side members 10 13 and 14. The pins protruding from the sides of combs 38 and 39 engage in slots 36 and 37, plates 34, and tend to guide the combs in the channels formed by side plates 34 and side arms 27, as illustrated in Figures 5, 6 and 10.

20 The movement of comb 23 is transmitted to combs 38 by means of equalizing bar 44 as more clearly illustrated in Figure 2. Similarly the movement of comb 24 in the opposite direction, is transmitted to combs 39 by means of equalizing bar 45. Figure 6 illustrates the final position of the various parts after the completion of the movements described and coil 50 is now set to the shape illustrated in Figures 2 and 7. End combs 40, with the restraining pins 42 removed, are drawn towards each other as coil 30 35 50 assumes the set shape. This is illustrated by solid lines in Figure 2. The end combs 40 are collapsible to facilitate the removal of the wound coils. These end combs are moved to their collapsible positions as follows.

Handle 22 is now removed and end combs 40 are individually moved the remaining distance against the side arms 27 disengaging them from coil 50. Coil 50 may then be easily removed 40 from the rest of the winding combs and withdrawn over end plate 46 and removed from this winding device. End plate 46 may be provided in various sizes, determined by the size of the coil to be wound, so as to facilitate removal of 45 the wound and set coils.

It will be noted that the coils 50 in Figure 7, appear shorter than coils 49 of Figure 12, due to the setting operation of the wound coils to the preferred shape. In Figure 8, coils 50 show 50 how the setting operation forms coils to a shape that permits nesting together which is desirable for fields of electric motors or the like.

I am aware that the improvements illustrated in the foregoing description are capable of considerable modification in structural details. I therefore, do not desire that this invention be limited to the details described but be construed as broadly as the prior art will permit.

Having thus described my invention, I claim:

- 60 1. A device of the class described, comprising a cross head, a fixed arm connected with said cross head, a plurality of movable arms adjustably connected with said cross head, movable winding combs mounted on said arms and adjustable collapsible end combs which are moved toward each other to facilitate the removal of wound coils.
2. A device of the class described comprising a cross head, a fixed arm projecting laterally from said cross head, two adjustable arms projecting laterally from said cross head, one on each side of said fixed arm, two winding combs slidably connected with the fixed arm and with the adjustable arms, means for sliding the winding combs on the fixed arm in opposite directions 70 75

tions and a connection between said latter winding combs and the winding combs on the adjustable arms by means of which the winding combs on the fixed arms are moved.

3. A device of the class described comprising a cross head, a fixed arm projecting laterally from said cross head, two adjustable arms projecting laterally from said cross head, one on each side of said fixed arm, two winding combs slidably connected with the fixed arm and with the adjustable arms, means for sliding the winding combs on the fixed arm in opposite directions and a connection between said latter winding combs and the winding combs on the adjustable arms by means of which the winding combs on the fixed arms are moved, and an end winding comb adjustably connected with each of said adjustable arms.

4. An apparatus for forming armature coils comprising a rotatable support, a central laterally projecting member connected with said support and fixed against rotation with relation to said support, laterally extending members on opposite sides of said central member and adjustably connected with said support and fixed against rotation with relation to said support, two sets of winding combs slidably connected with said central member, one on each side thereof, means for sliding said winding combs in opposite directions along said central member, two sets of winding combs on each of said adjustable members, one on each side thereof, and means for sliding them in opposite directions along said adjustable members, the coils being formed by winding wire on said winding combs.

5. An apparatus for forming armature coils comprising a rotatable support, a central laterally projecting member connected with said support and fixed against rotation with relation to said support, laterally extending members on opposite sides of said central member and adjustably connected with said support, two sets of winding combs slidably connected with said central member, one on each side thereof, means for sliding said winding combs in opposite directions along said central member, two sets of winding combs on each of said adjustable members, one on each side thereof, means for sliding them in opposite directions along said adjustable members, the coils being formed by winding wire on said winding combs, and means at opposite ends of the coils for holding them against lateral movement when the combs are moved along said members.

6. An apparatus for forming armature coils comprising a rotatable support, a central laterally projecting member connected with said support and fixed against rotation with relation to said support, laterally extending members on opposite sides of said central member and adjustably connected with said support and fixed against rotation with relation to said support, two sets of winding combs slidably connected with said central member, one on each side thereof, means for sliding said winding combs in opposite directions along said central member, two sets of winding combs on each of said adjustable members, one on each side thereof, means for sliding them in opposite directions along said adjustable members, and combs projecting from the sides of said adjustable members and fixed against longitudinal movement with relation thereto, the coils being formed by winding wire on said winding combs.

7. An apparatus for forming armature coils

comprising a rotatable support, a central laterally projecting member connected with said support and fixed against rotation with relation to said support, laterally extending members on opposite sides of said central member and adjustably connected with said support and fixed against rotation with relation to said support, two sets of winding combs slidably connected with said central member, one on each side thereof, means for sliding said winding combs in opposite directions along said central member, two sets of winding combs on each of said adjustable members, one on each side thereof, means for sliding them in opposite directions along said adjustable members, and combs projecting from the sides of said adjustable members and fixed against longitudinal movement with relation thereto, said latter combs adjustable to and from said adjustable members, the coils being formed by winding wire on said winding combs.

8. A coil forming machine comprising three projecting members in substantial parallel arrangement one of them being a central member located between the other two, said members being relatively adjustable to and from each other, two winding combs on the central member, projecting in opposite directions therefrom, two winding combs associated with the adjustable members and projecting in opposite directions therefrom, means for moving the winding combs associated with one member in opposite directions therealong, and a movable connection between said combs and the combs associated with the other members so that all the combs move simultaneously.

9. A coil forming machine comprising three

projecting members in substantial parallel arrangement one of them being a central member located between the other two, said members being relatively adjustable to and from each other, two winding combs on the central member, 5 projecting in opposite directions therefrom, two winding combs associated with the adjustable members and projecting in opposite directions therefrom, means for moving the winding combs associated with one member in opposite 10 directions therealong, a movable connection between said combs and the combs associated with the other members so that all the combs move simultaneously, and a comb connected with each of the adjustable members and fixed against 15 longitudinal movement therealong.

10. A coil forming machine comprising three projecting members in substantial parallel arrangement one of them being a central member located between the other two, said members being relatively adjustable to and from each other, two winding combs on the central member, 20 projecting in opposite directions therefrom, two winding combs associated with the adjustable members and projecting in opposite directions 25 therefrom, means for moving the winding combs associated with one member in opposite directions therealong, a movable connection between said combs and the combs associated with the other members so that all the combs move 30 simultaneously, and a comb connected with each of the adjustable members and fixed against longitudinal movement therealong, said latter combs being movable to and from the adjustable members.

WILLIAM KAUPPERT. 35
